UNITED STATES PATENT OFFICE.

ANTHONY VASSELLI, OF NEWARK, NEW JERSEY, ASSIGNOR, BY MESNE ASSIGNMENTS, TO HARRIMAN NATIONAL BANK OF THE CITY OF NEW YORK, TRUSTEE.

TONE-ARM FOR TALKING-MACHINES.

1,350,753.

Specification of Letters Patent. Patented Aug. 24, 1920.

Application filed January 17, 1918. Serial No. 212,236.

To all whom it may concern:

Be it known that I, ANTHONY VASSELLI, a citizen of the United States, and a resident of the city of Newark, county of Essex, and 5 State of New Jersey, have invented a certain new and useful Tone-Arm for Talking-Machines, of which the following is a specification.

My invention relates to tone arms for 10 talking machines, and more particularly to tone arms which are provided with joints whereby the position of the sound box may be changed from playing position in order to facilitate inserting or removing the 15 producer point, and wherein the sound box will be locked in the latter position.

I am aware that it has been suggested to 20 lock the sound box in raised position, but in all of such devices should the operator neglect to lower the sound box before the lid or cover of the cabinet is closed, the inner side of the lid will be marred and scratched by coming in contact with the sound box, and if considerable force be applied to the cover, the tone arm or sound 25 box, or both, may be broken or injured.

The object of my invention is to provide 30 means whereby the sound box will be locked in raised position in such a manner that when engaged by the cover it will be moved from such raised position.

A further object is to provide means 35 whereby when in lowered position, the sound box while being free to move vertically relatively to the record disk, will be prevented from being accidentally moved into engagement with the cover when the latter is in closed position.

A further object of the invention is to 40 provide a device of the character described, which is extremely simple in construction, thoroughly reliable and efficient securing means, and inexpensive to manufacture.

With these and other objects in view, to be 45 more fully set forth hereinafter, the invention consists in the novel construction, combination of elements, and arrangement of parts which will be exemplified in the construction hereinafter described in the 50 specification and illustrated in the accompanying drawings considered together or separately.

I have illustrated one embodiment of my invention in the accompanying drawings in 55 which like parts in all the figures are design-

nated by similar reference characters, and in which,—

Figure 1 is a side elevation partly in section of a tone arm provided with my invention, the section being taken on the line 60 1—1 of Fig. 2; and

Fig. 2 is a fragmentary sectional view taken on the line 2—2 of Fig. 1.

In carrying out my invention, I employ 65 a tone arm 1 of ordinary construction, and having a slightly upturned outer extremity 2. Pivoted on a pin 3 in the end 2 of the tone arm is a tubular member 4. The tubular member 4 is of less outer diameter than the inner diameter of the extremity 2 of the 70 tone arm. The inner end of the tubular member 4 is provided with a spherical portion so as to closely fit the interior of the tone arm 1 at the extremity 2 and be capable of angular movement relatively to the axis 75 of the tone arm.

Inserted in the outer extremity of the tubular member 4 is an elbow 5 of less diameter than 4. The joint 5 may be rigidly secured in the elbow 4, or it may be relatively movable therein in order that the 80 plane of the sound box may be changed to play either lateral or vertical cut records.

A hollow member 6 of smaller diameter 85 than the elbow 5 is rigidly secured in the outer extremity of the latter, and carries a sound box or reproducer 7 of any approved type. The sound box is provided with the usual diaphragm, stylus arm and stylus. 90

Extending across the tone arm 1, a short distance to the rear of the pin 3 is a similar pin 8 which may be threaded into the side wall of the tone arm. A sleeve 9 is carried by the pin 8, and is secured thereto by means 95 of a set screw 10. The sleeve has a reduced portion 11 which engages a slot 12 in a lever 13 which is thereby pivoted on the sleeve and is capable of movement relatively of the sleeve and pin in the direction longitudinally of the lever 13. 100

The front extremity of the lever 13 has a cam face 14 which engages the inner end 15 of the tubular member 4. A spring 16 is secured to the sleeve 9 and the rear extremity of the lever 13 by being set in a recess and having a portion of said spring bent over on the side of the lever. This spring tends to hold the rear end of the slot 12 in contact with the pin 8, so that 110

when the sound box 7 is in the position shown in full lines in Fig. 1, the cam face 14 will engage beneath the pin 3, and hold in such position.

5 A washer 17 is riveted in place on the end of the reduced portion of the sleeve 9 and retains the lever 13 in place.

An inspection of Fig. 2 will show that the lever 13 is in the longitudinal center of 15 the tone arm.

The lower edge of the extremity 2 of the tone arm has a notched portion 18 to permit the tubular member 4 to swing downwardly when desired. This notched portion may 15 be omitted if it is not desired to swing the tubular member as far as shown, or it may be made deeper if more movement be desired.

The operation is as follows:

20 The parts being in the position shown in dotted lines in Fig. 1, the sound box may be raised slightly so as to place the stylus in the record groove, and the sound box may freely move vertically by reason of the unevenness of the record disk. This is made possible by reason of the lost motion at the point *a*. The end of the tubular member 4 may travel downward a short distance before it engages the cam 15. At the same time the sound box is prevented from falling 25 lower by the engagement of the tubular member with the underside of the lever at *b*. It being understood that the rear end of the lever is in engagement with the wall of the tone arm near the bottom thereof.

30 35 Further upward movement of the sound box will engage the point *a* with the cam face of the lever and force it back against the tension of the spring 16. As the inner end of the tubular member proceeds downward, 40 it will ride over the top of the cam 14 and the spring will move the lever forward so that its front upper corner will engage beneath the pin 3.

45 When the sound box is released, it will fall until the end of the tubular member engages the cam face at *c*. This will prevent farther downward movement of the sound box by gravity as the weight will not be sufficient to force the end of the lever from beneath the pin 3.

50 Should the cover (not shown) be closed when the sound box is in the position shown in full lines, the weight of the cover on the sound box will cause the edge of the tubular member 4 to rise along the cam face 14 and push the lever 13 backward against the tension of the spring 16 and release the forward end of the lever from its position beneath the pin 3. As the lever is raised above the 60 pin, the spring will move it forward to again engage the tubular member 4, and hold the same in the position shown in the dotted lines.

65 In accordance with the provisions of the patent statute, I have described the prin-

ple of my invention together with the apparatus which I now consider to represent the best embodiment thereof, but I desire it understood that my invention is not confined to the particular form of apparatus 70 herein shown and described, and, therefore, I claim broadly the right to employ all equivalent instrumentalities coming within the scope of the appended claims, and by means of which objects of my invention are 75 attained, and the new results accomplished, as herein set forth, as it is obvious that the particular embodiment herein shown and described is only one of many that can be employed to attain these objects and accomplish these results.

Having now described my invention, what I claim and desire to secure by Letters Patent is,—

1. A tone-arm having a pivoted member, 85 a spring actuated lever within the tone-arm for securing the member in a predetermined position, said member extending within the tone-arm to engage the lever and adapted to move the same to release the member. 90

2. A tone-arm having a pivoted member, 95 said member extending within the tone-arm, a lever pivoted within the tone-arm, means for moving the lever in one direction to engage the same with the member, and means whereby movement of the member will permit of movement of the lever from its engagement with the member.

3. A tone-arm, a member extending within the tone-arm, and pivoted in the same, a 100 pin within the tone-arm, a lever pivoted on the pin, a spring adapted to move the lever in one direction to engage the same with the member and with the pin, a cam face on the lever in engagement with the member, 105 whereby movement of the member will cause the lever to be moved from its engagement with the member and pin.

4. A tone-arm, a member pivoted in the extremity of the tone-arm, a lever within the tone-arm, said lever engaging the member and being movable by the pivotal movement of the member, the engagement of the member with the lever being within the tone-arm. 110

5. A tone-arm, a member pivoted in the extremity of the tone-arm, a lever within the tone-arm, and capable of movement longitudinally and transversely of the tone-arm, said lever engaging the member and being movable longitudinally by the pivotal movement of the member, and means within the tone-arm for moving the lever transversely of the tone-arm. 120

6. A tone-arm, a member pivoted in the 125 extremity of the tone-arm, a pivoted lever within the tone-arm and capable of bodily movement longitudinally and pivotal movement transversely of the tone-arm, said lever engaging the member, and means whereby 130

pivotal movement of the member will bodily move the lever longitudinally of the tone arm.

7. A tone arm, an element extending with-
5 in the tone arm, a tubular member pivoted on the element, a pin extending across the tone arm, a lever pivoted on the pin, there being a slot in the lever engaging the pin, a
10 spring for moving the lever in one direction to engage the same with the element, a cam

face on the lever in engagement with the member, whereby movement of the member will move the lever from its engagement with the element.

This specification signed and witnessed 15
this 4th day of January, 1918.

ANTHONY VASSELLI.
